UNITED STATES PATENT OFFICE.

MARCEL ACHILLE VIOLET, OF LEVALLOIS-PERRET, FRANCE.

IGNITING DEVICE FOR EXPLOSION-MOTORS.

1,326,810.

Specification of Letters Patent. Patented Dec. 30, 1919.

Application filed June 21, 1917. Serial No. 176,127.

To all whom it may concern:

Be it known that I, MARCEL ACHILLE VIOLET, a citizen of the Republic of France, residing at 67 Rue Rivay, Levallois-Perret, 5 Seine, in the Republic of France, have invented certain new and useful Improvements in Igniting Devices for Explosion-Motors; and I do hereby declare the following to be a full, clear, and exact description 10 of the invention, such as will enable others skilled in the art to which it appertains to make and use the same, reference being had to the accompanying drawings, and to letters or figures of reference marked thereon, 15 which form a part of this specification.

In many cases explosion motors must be provided with a very expensive magneto, the cost of which sometimes exceeds that of the motor itself. The object of this invention is 20 to do away with the inconvenience while obtaining some additional advantages.

These results are attained by means of a device shown by the annexed drawings, in which Figure 1 is a part longitudinal section of an explosion motor embodying the invention. Fig. 2 is an end elevation, and Fig. 3 is a side elevation of a four cylinder explosion eng. illustrating the invention.

It is to be observed that in a multicylinder 25 two stroke motor, only one piston at a time comes in the compression position, by contradistinction with what is the case in a four stroke motor for instance, where a pair of pistons are in the same position at a time. 30 Therefore by providing a two stroke four cylinder motor with a magneto without any distributor and giving two sparks at every revolution against a collecting ring and a single contact piece, and by causing such 35 magneto to rotate twice faster than the motor, the four sparks per revolution which are necessary for the working of the motor will be obtained.

In order to distribute the sparks to the 40 cylinders in proper time, it is sufficient to provide the latter with sparking plugs having a central insulated electrode *a* which latter is separated from the body *b* of the plug by a distance which cannot be traversed by the spark, and is so positioned that when each piston reaches the compression 45 position (as shown in the drawing) the deflector *c* of the piston *d* is a very short distance apart from said electrode.

Consequently, if all the sparking plugs 50 are connected to the magneto by a single wire *e*, it is clear that the spark produced at

each quarter of a revolution will pass between that plug and that piston which are in relation together.

60

On the crank shaft *g* of the four cylinder engine *f* is mounted a gear wheel *h* twice the diameter of the gear wheel *i* that drives the armature of the magneto *j*, current from which is taken by a single wire *e* to all the 65 spark plugs *b* of the four cylinders.

A two stroke motor has been referred to above by way of example, but it is obvious that the igniting device under the invention is also applicable to the four stroke motors; 70 a spark out of two will not in that case be utilized, that is all.

This invention procures the following advantages:

The magneto without any distributor can 75 be a very small one without interfering with the ready starting of the motor, as said magneto rotates twice faster than the latter. This means simplicity and cheapness.

On the other hand, as the spark is produced between two moving surfaces, the wear is even and very small and any fouling due to carbon deposits is impossible by the very fact of the electrodes being movable.

Moreover, the igniting device is very 85 strong.

Lastly, the user of the motor does not run the risk of wrongly connecting the wires, which is a frequent cause of interruption in the working of the motor.

90

Having thus described my invention, what I claim as new and desire to secure by Letters Patent is:

In a plural cylinder two-stroke explosion engine, the combination with the cylinders 95 thereof; of a spark plug extending into the compression space of each cylinder, a piston having a reduced end extending into the compression space of each cylinder, a deflector operating as a non-wiping contact on 100 each piston end arranged to move in sparking relation to its plug a single wire common to all of said plugs, current generating means operating at double the speed of the engine, and means to send current 105 through said wire at each quarter cycle of operations.

In testimony that I claim the foregoing as my invention I have signed my name in presence of two subscribing witnesses.

MARCEL ACHILLE VIOLET
